UNITED STATES PATENT OFFICE

WILLIAM A. GEIGER, OF CHICAGO, ILLINOIS, ASSIGNOR TO W. H. MINER, INC., OF CHICAGO, ILLINOIS, A CORPORATION OF DELAWARE

CAR CONSTRUCTION

Application filed January 28, 1929. Serial No. 335,449.

This invention relates to improvements in car construction.

One object of the invention is to provide a combined locking and center pin arrangement for railway cars of rugged design, including a connecting element comprising a plurality of sections and a spacing member, certain of the sections having shouldered engagement with the car bolsters to prevent separation thereof, the sections when collapsed by removing the spacing member being of such dimensions in cross section that they will pass freely through the center pin receiving openings, the shouldered engagement between the sections and the cooperating bolster being provided by a tapered seat on the bolster and cooperating expanded tapered head portions on said sections.

Another object of the invention is to provide means for connecting the body and truck bolsters of railway cars including a sectional center pin comprising outer sections and a spreading member, said outer sections being interlocked with the cooperating bolster by a tapered head of greater size than the main shank portion of the pin and cooperating with a tapered seat on the bolster, portions of said head being formed on each of the outer sections and the sections being held apart by the spreading member to lock the head to the bolster, said outer sections being collapsible when the spreading member is withdrawn from between the same to reduce the cross sectional area of said tapered head to permit insertion of the parts through the pin receiving openings of the bolsters.

A further object of the invention is to provide a center pin construction for connecting the body and truck bolsters of a railway car provided with aligned center pin receiving openings, wherein the pin is headed at opposite ends to interlock the same with both bolsters and is collapsible to reduce the size of each of the heads to permit insertion of the parts through the pin receiving openings, by entering the same either through the body or truck bolster opening, one of said head members being tapered and cooperating with a tapered seat on the corresponding bolster.

A more specific object of the invention is

to provide a combined locking and center pin arrangement for body and truck bolsters of railway cars, including a pin proper composed of a pair of counterpart outer sections and a spreading member interposed therebetween, each of the outer sections having enlargements at the opposite ends thereof forming portions of head members by which the sections are anchored to both bolsters, one of said heads being tapered, increasing in size toward the extremity of the pin, and the cooperating bolster being formed with a tapered seat for said head, whereby, when the spreading member is withdrawn from between said sections, the latter are collapsible to effect reduction in size of the pin, the tapered head member being of such cross sectional area that the sections pass through the pin receiving opening of the bolster when the parts are collapsed.

Other and further objects of the invention will more clearly appear from the description and claims hereinafter following.

In the drawing forming a part of this specification, Figure 1 is a top plan view of the body and truck bolsters of a railway car, illustrating my improvements in connection therewith. Figure 2 is a vertical sectional view, corresponding substantially to the line 2-2 of Figure 1. Figure 3 is a horizontal transverse sectional view, partly broken away, corresponding substantially to the line 3-3 of Figure 2. And Figure 4 is a detailed elevational view of a spreading or filler member employed in connection with my improved combined locking and center pin construction.

In said drawing, 10 indicates generally a portion of the body bolster of a railway car and 11 the cooperating truck bolster. The body bolster is provided with the usual top and bottom webs and a cylindrical sleeve section 12 connecting the same. At the bottom, the bolster 10 is provided with a downward projection 13 having a substantially spherical bearing surface cooperating with a spherical bearing seat 14 formed on a bearing block 15 seated in a pocket 16 on the truck bolster.

The truck bolster 11 is also provided with

the usual top and bottom webs connected by a central sleeve-like section 17. The body and truck bolsters are provided with center pin receiving openings and an aligned opening 5 in the bearing plate 15, the opening in the bearing plate being surrounded by an upstanding annular flange 18 which engages within a seat 19 formed on the bottom of the body bolster.

10 In carrying out my invention, I provide the truck bolster with a center pin receiving opening 20 which is of smaller diameter than the main portion of the sleeve-like section 17, whereby a pocket 21 is provided to accommodate the head member at the lower end 15 of the center pin. An annular shoulder 22 is thus provided in the pocket surrounding the center pin receiving opening 20. The bearing plate 15 is provided with a center pin receiving opening 23 of the same diameter as 20 the opening 20.

The walls at the bottom portion of the sleeve section 12 of the body bolster are thickened, as clearly shown in Figure 2, and said 25 lower end portion of the sleeve is provided with a center pin opening 24 of substantially the same diameter as the openings 20 and 23. Immediately above the opening 24, the inner 30 faces of the walls of the sleeve 12 are flared upwardly to provide a tapered seat 25 which cooperates with the center pin member, as hereinafter more clearly pointed out. Above the tapered seat 25, the opening in the bolster may be made of larger diameter than the 35 upper portion of the seat, or said opening may be made of the same diameter as the upper portion of the seat.

40 My improved combined center and locking pin proper comprises a pair of counterpart outer sections A—A and a central section B which forms a filler or spreading member.

Each of the sections A has a central shank portion 26 and a laterally outwardly projecting flange 27 at the bottom end thereof. 45 At the upper end, each section is enlarged, as indicated at 28. The enlargement 28 of each section fits the corresponding side of the tapered seat 25 of the bolster 10, as clearly illustrated in Figures 1 and 2.

50 On the inner sides, the sections A present flat vertical faces which, when brought into abutment by displacing one section laterally inwardly, reduce the cross sectional area of the head formed by the flange portions 27 55 at the bottom ends of the sections A and the cross sectional area of the retaining means formed by the enlargements 28 at the upper end of said sections, so that the displaced section A may be withdrawn, the head portion 60 at the bottom end of said section and the retaining means at the top end thereof being of such a size as to pass freely through the pin receiving openings 20, 23 and 24. The remaining section may then be displaced 65 laterally to register the flange and enlarge-

ment thereof with the pin receiving openings, and is then withdrawn in a similar manner. As will be clear upon reference to Figures 1 and 3, the opposite side portions of the head formed by the flanges 27, as well as the opposite side portions of the retaining means formed by the enlargements 28, are cut away so as to provide proper clearance to permit the flanges and enlargements of the sections A to pass through the pin receiving openings of the bolsters. 70

75 The filler or spreading member B is in the form of a relatively thick plate having upwardly diverging side edge portions 29 adjacent the upper end thereof, which are adapted to seat on the opposite side walls of the tapered seat 25 to limit downward movement of said member B. The member B is of such a thickness that it will hold the sections A separated to such an extent that the flanges 27 will overhang the annular shoulder 22 and that the tapered enlargements 28 will be seated on the walls of the tapered seat 25.

80 In order to facilitate the removal of the member B, the same is preferably provided with an upstanding lug-like member 30 at the upper end thereof, provided with an opening 31 adapted to cooperate with the hook portion of a tool by which the member B may be lifted upwardly. 85

85 The outer sections A are also preferably provided with similar lugs 32—32 having openings 33—33 within which a tool may be engaged to lift the same out of the opening 100 in the bolster 10.

90 In assembling my improved combined locking and center pin with the body and truck bolsters of a railway car, one of the sections A is first inserted through the center pin openings of the bolsters and displaced laterally to overlap the flange 27 with the shoulder of the truck bolster and seat the head section 28 on the tapered seat portion 25. The other section A is then inserted, the 95 inner side thereof being at this time in contact with the inner side of the section A first applied, so as to reduce the cross sectional area of the head member and the tapered retaining means, as hereinbefore pointed out, 100 so that the flange and enlargement of the last named section will pass through the pin receiving openings of the bolsters. As will be evident, the sections A may be applied by inserting the same in succession through the 105 top of the body bolster and passing the flanges at the lower ends thereof through said pin receiving openings until the same are disposed below the annular shoulder 22 of the truck bolster, or by inserting the sections successively upwardly through the opening of the truck bolster and passing the enlargements 28 through the pin receiving openings until said enlargements register with the seat 25. When the parts have been thus far 110

115 120 125 130

assembled with the body and truck bolsters, the sections A are spread apart and the filler or spreading member B inserted therebetween by passing the same downwardly through the opening in the body bolster. 5 The sections will thus be held apart with the flanges 27 in overlapping relation with the annular shoulder 22 and the enlargements 28 seated on the opposite side wall portions 10 of the seat 25, thereby anchoring the pin to both bolsters and preventing separation of the latter.

When it is desired to separate the bolsters, the pin is readily removed by withdrawing 15 the member B from between the sections A and then collapsing the sections by displacing one of the same laterally inwardly and bringing them into contact, whereupon the displaced section may be first withdrawn, the 20 other section being then displaced laterally inwardly to register the enlargement and flange thereof with the pin receiving openings, whereupon said last named section may be withdrawn. As will be evident, the sections 25 may be withdrawn either through the opening in the body bolster or the opening in the truck bolster.

Although the means for locking the pin to the bolsters is shown as comprising a tapered 30 head member at the upper end and an ordinary shouldered head at the lower end, it will be appreciated that it is within the invention to provide tapered heads at both ends of the pin which cooperate with tapered seat members on both bolsters. It is also pointed out 35 that the member B may be inserted through the opening in the truck bolster, instead of through the opening in the body bolster, as shown, it being merely necessary to form the member of the same width from top to bottom, eliminating the inclined edge portions 29 and providing any well known retaining 40 means for limiting the downward movement of said member.

While I have herein shown and described 45 what I now consider the preferred manner of carrying out my invention, the same is merely illustrative and I contemplate all changes and modifications which come within the scope of 50 the claims appended hereto.

I claim:

1. In car construction, the combination 55 with body and truck bolsters having aligned center pin receiving openings; of a pin having a tapered head cooperating with a tapered seat on one of said bolsters to prevent removal of the pin in one direction and means at the other end of the pin cooperating with the other bolster to prevent removal of said pin in a reverse direction, said pin comprising a plurality of sections including a spreading member which when removed permits collapse of the pin to effect reduction in size of 60 said tapered head to allow passage thereof through the pin receiving openings.

2. In car construction, the combination 70 with body and truck bolsters having aligned center pin receiving openings; of a pin having a tapered head cooperating with a tapered seat on one of said bolsters to prevent removal of the pin in one direction and a head at the other end of the pin cooperating with the other bolster to prevent removal of said pin in a reverse direction, said pin comprising a plurality of sections including a removable filler member which when withdrawn permits collapse of the pin, said heads being formed 75 partly on each of said sections, said parts of the heads being of such a cross sectional size as to pass through said pin receiving openings.

3. In car construction, the combination 80 with body and truck bolsters having aligned center pin receiving openings, one of said bolsters having a shoulder adjacent its opening and the other bolster having a retaining means thereon, said retaining means including outwardly expanded wall sections defining a seat; of a center pin comprising a pair of outer sections and a center filler member, said pin having a head at one end cooperating 85 with said shoulder, parts of said head being formed on each of said sections, an outwardly expanded section at the other end of the pin fitting said seat, part of said expanded section being formed on each section of the pin, the shape of said expanded section being such that the outer sections of the pin may be inserted through said openings when said filler member is withdrawn and the sections are collapsed, but are prevented from passing 90 through said openings when said filler member is interposed between said sections.

4. In car construction, the combination 95 with body and truck bolsters having aligned center pin receiving openings, each of said bolsters having a retaining means adjacent its opening forming an integral part of the corresponding bolster; of a sectional center pin comprising a pair of outer members and a central filler member, said sectional pin having retaining means at one end cooperating 100 with the retaining means of one of said bolsters and a tapered portion at the other end having wedging engagement with the retaining means of the other bolster.

5. In car construction, the combination 110 with body and truck bolsters having aligned center pin receiving openings, one of said bolsters having a shoulder adjacent the opening and the other bolster having a tapered seat adjacent its opening; of a collapsible center pin including a removable filler section, said center pin extending through said openings and having means at one end thereof in wedging engagement with said seat, the other end of said pin having a head cooperating 115 with the shoulder, the wedge portion of said pin being of such a size when the pin is collapsed by removal of said filler as to permit 120

removal of the remainder of said pin from pin receiving openings of the bolsters.

6. In car construction, the combination with body and truck bolsters having aligned openings adapted to receive a center pin, the openings of one of said bolsters having a shoulder adjacent thereto and the opening of the other bolster having opposed wall portions thereof outwardly flared; of a sectional center pin extending through said openings, one of the sections of said pin being removable to permit reduction in cross sectional area of said pin, the remaining sections of said pin having enlargements at opposite ends thereof, said pin having a shank portion fitting the opening having the shoulder, the corresponding end of the pin having a head formed by said enlargements at one set of ends of said sections cooperating with said shoulder, the other end of the pin having a tapered section formed by the enlargements at said end, said last named enlargements passing through said openings when said removable section is withdrawn, but being prevented from passing through said openings when all of said sections are in assembled relation and said tapered section is in overhanging relation with respect to said flaring walls.

7. In car construction, the combination with body and truck bolsters having aligned center pin receiving openings, one of said bolsters having a tapered retaining seat thereon adjacent the opening thereof; of a center pin composed of a pair of outer members and an intermediate spacer, said outer members having enlargements at one set of ends forming an expanded head portion fitting said seat, said outer members having means at the other end for preventing removal from the other bolster, the shape of said expanded head of the pin, when said intermediate spacer is removed and the outer sections are collapsed, and the shape of said openings and said seat being such that parts of the pin may be inserted through said openings, but are prevented from passing therethrough when said spacer is interposed between said outer sections to engage said enlargements with said seat.

8. In car construction, the combination with body and truck bolsters having aligned center pin receiving openings, one of said bolsters having an outwardly flared seat coalescing with its opening; of a multiple-part center pin adapted to be disposed in said openings, said pin including a removable spreading member and additional elements, said elements, at one set of ends, having outwardly flared portions adapted to engage and fit with said outwardly flared seat of the corresponding bolster when the spreading member is in operative position to thereby prevent removal of the pin in one direction through said openings; and means at the opposite

end of said pin for preventing removal of the pin in the opposite direction when the spreading member is in place.

In witness that I claim the foregoing I have hereunto subscribed my name this 24th day of January 1929.

WILLIAM A. GEIGER.
